CONTROL APPARATUS FOR GANG CONDENSERS

Filed Oct. 11, 1929

UNITED STATES PATENT OFFICE

THEODORE J. SCOFIELD AND WILLIAM D. MINER, OF JACKSON, MICHIGAN, ASSIGNORS
TO SPARKS-WITHINGTON COMPANY, A CORPORATION OF OHIO

CONTROL APPARATUS FOR GANG CONDENSERS

Application filed October 11, 1929. Serial No. 398,864.

This invention relates to control apparatus for gang condensers and the like in radio receiving sets.

An object of the invention is to construct a control device with indicating means that will be of pleasing appearance, rigid construction and of low cost and capable of rapid assembly.

Other objects will appear in the following specification, reference being had to the drawing, in which:

Fig. 1 is an end view of the complete assembly of control and indicating device.

Fig. 2 is a front view of the hub and spider member forming the frame of the device.

Fig. 3 is an edge view of the device shown in Fig. 2.

Fig. 4 is a view of the rear side plate as seen from the rear of Fig. 1.

Fig. 5 is a view of the front side plate as seen from the front of Fig. 1.

Fig. 6 is a partial sectional view of the complete assembly taken on the line A—A of Fig. 1, the apparatus being viewed from the left of Fig. 1.

Fig. 7 is a development of the celluloid strip placed around the drum for indicating the adjustment of the control member.

Radio receiving sets as now made contain a plurality of condensers with the rotors joined together by a common rotatable shaft. The condensers are not shown in the drawing but 1 indicates a section of the shaft of such a gang condenser. On the shaft is a spider 2, which is preferably die-cast. This spider has a hub 3 fitting over the shaft 1 and has a projection 4 adapted to receive the central hole of the front side flange to be later referred to. The hub has a reinforcing flange 5 having holes therein to be attached to the inside flange shown in Fig. 4. The spider has radial reinforcing ribs or spokes 6 joined together by a web portion in which there may be holes 7 to make a light construction and reduce the amount of metal necessary. The ribs and web portion are joined to an arcuate member 8. The arcuate member 8 has radially projecting lugs 9 and 10 to receive the ends 11 and 12 of the celluloid or other strip shown in Fig. 7. Screws 13 and

washers 14 such as shown in Fig. 6 clamp the ends of the strip to the lugs in cooperation with slots 15 in the ends of the strip.

The rear disc flange 16 (Fig. 4) is preferably stamped from thin metal so that it has a peripheral groove 17 for reception of the adjusting cable to be later referred to. After being stamped downwardly and thence upwardly to form the groove 17 the outer portion of the disc 16 extends radially outward and is forced over in an axial direction first outwardly and then inwardly to form a side groove 18 for reception of the celluloid strip 11. The rear disc 16 has a plurality of holes 19 adapted to line with the holes 20 in the flange of the spider. The flange 16 has the periphery notched at 21 to permit the insertion and removal of the celluloid indicating strip.

The front disc flange 22 is stamped similarly to the disc 16 to form peripheral groove 23 and side groove 24 but it has a portion cut away to leave web 25. The cutaway portion permits the insertion of a lamp (not shown) to illuminate the dial.

The front disc member has holes 26 aligning with holes 27 of the spider member and holes 28 of the inside disc member. The member 22 also has a notch 29 adapted to line with the notch 21 when the parts are assembled so that the strip 11 can be inserted and withdrawn. In assembling the apparatus the disc 16 is placed in proper position against the rear of the spider, as shown in Fig. 2. These two parts are then fastened together by tight fitting pins driven through the member 16 into the rear ends of holes 27 or in some cases lugs may be die-cast at the rear of the holes 27 to take the place of these pins. In the latter the lugs would be peened over to hold the member 16 rigidly in place.

The front disc member 22 is then placed in position with its central hole 31 fitting over projection 4 of the spider and with the holes 26 in alignment with the holes 27, which latter are threaded. Screws are then threaded into the holes 27 to clamp the front member tightly in position.

After the parts are assembled as just described the entire drum is pushed on to shaft 100

1 of the gang condenser and screw drivers are inserted through holes 32 in the spider to adjust set screws 33 to clamp the drum tightly against the shaft. The celluloid or 5 fibre strip 11 is then inserted in the grooves 18 and 24 commencing at notches 21 and 29. If the strip binds it can be readily pushed into position by inserting the fingers through the opening or cut-out portion of the front 10 member 22. Also, if the strip binds the screws threaded in the holes 27 may be loosened and retightened when the strip is in position. When the strip is assembled the grooves 15 will be in position on lugs 9 and 10 and screws 15 13 pressing against washer 14 will thread into these lugs and clamp the strip in position.

The arrangement of parts is such that complete drum even with the celluloid strip in 20 position can be readily removed or attached to the shaft 1 because the holes 32 are not covered up by any of the assembly.

When the assembled indicating drum is in 25 position on shaft 1 a cable or cord 33' has one end fastened to screw sheave or drum 34 around which it may be wrapped one or more times. The cord then passes around a portion of the groove 23 thence through the hole 35 in front member 22, and a portion 33a 30 extends around lug 10 and thence through hole 36 into rear member 16. The cable or cord then passes around groove 17 and is attached to screw sheave 35' after passing around it one or more times. One of the screw 35 drums, for example, 35, is clamped against control shaft 36' by set screws 37 preferably arranged at right angles, as shown in Fig. 1. The other drum may be pressed tightly on the shaft as the adjustment of one drum is sufficient to permit assembly of the cable with the desired tautness. The control shaft 36 is attached to knob 38, as shown in Fig. 1. The control shaft 36 is attached to knob 38 preferably in accordance with the invention of 40 "control knobs", described in application No. 403,528, filed October 30, 1929, though, of course, other fastening means may be used.

Having described our invention what we claim is:

- 50 1. In indicating drums for condensers and the like, disc flanges bent downwardly and thence upwardly to form driving grooves, and at an outer portion bent outwardly and then inwardly to form side grooves, means 55 for securing said flanges together with the side grooves facing each other and an indicating strip secured in said side grooves.
- 55 2. In indicating drums for condensers and the like, disc flanges bent downwardly and 60 then upwardly to form driving grooves, and an outer portion bent outwardly and then inwardly to form side grooves, a hub member having peripheral lugs, means to clamp said flanges to said hub member with the side 65 grooves facing each other, an indicating strip

in said side grooves and means to clamp the ends of said strip to said lugs.

3. In indicating drums for condensers and the like, disc flanges having central holes, bent downwardly and then upwardly to form 70 grooves, and at an outer portion bent outwardly and then inwardly to form side grooves, a hub member having a hole and peripheral lugs, means to clamp said flanges to said hub member with the side grooves facing each other, and with all said holes in alignment, an indicating strip in said side 75 grooves, and means to clamp the ends of said strip to said lugs.

4. In indicating drums for condensers and the like, disc flanges having driving grooves opening at the top and further grooves opening 80 at the side, means to join said flanges together with the side grooves facing each other, an indicating strip secured in said side 85 grooves, a shaft arranged at right angles to said flanges, sheaves on said shaft is alignment with the first mentioned groove and a cable secured in said first mentioned groove having an end passing around each sheave. 90

5. In radio dials a pair of flanges each having a circular groove on a side, and a circular groove on the opposite side, an indicating strip secured in said first mentioned 95 grooves and driving means passing around the second mentioned grooves.

6. In radio dials a pair of circular flanges, each having a portion extending radially inwardly and thence outwardly forming a 100 groove and another portion extending axially outwardly and thence inwardly to form a second groove, said flanges being adjacently arranged with the second mentioned grooves facing each other, an indicating strip in the last mentioned grooves and driving means in the first mentioned grooves. 105

7. A radio dial consisting of a hub, flanges secured to each side of said hub, each flange having an arcuate portion extending radially inwardly and thence radially outwardly to form a groove, each of said flanges also having an arcuate portion extending axially outwardly and thence inwardly to form a second groove, said first mentioned groove being on the outside of said flange and the second mentioned groove being on the inside thereof, an indicating strip in the second mentioned grooves and driving means in the first mentioned groove. 110

In testimony whereof, we have signed our names to this specification this 7th day of October 1929.

THEODORE J. SCOFIELD.
